UNITED STATES PATENT OFFICE.

ALFRED BONOM, OF PATERSON, NEW JERSEY.

FLEXIBLE AND INSULATING, SUPPORTING, AND REENFORCING RINGS FOR CROWN BLADES OF TURBINES.

Application filed September 19, 1921. Serial No. 501,859.

To all whom it may concern:

Be it known that I, ALFRED BONOM, a subject of the Republic of France, residing at Paterson, in the State of New Jersey, 5 United States of America, have invented certain new and useful Improvements in Flexible and Insulating, Supporting, and Reenforcing Rings for Crown Blades of Turbines; and I do hereby declare that the 10 following is a full, clear, and exact description of the invention, such as will enable others skilled in the art to which it appertains to make and use the same.

The present invention relates to new and 15 useful improvements in flexible and insulating, supporting and reenforcing rings for crown plates for turbines.

The primary object of the invention is the 20 provision of means for attaching the blades of a turbine to the rotors.

Another object of the invention is the provision of means for removably attaching the blades of a turbine to the rotors so 25 that they may be readily removed for replacement purposes or for repairing.

A further object of the invention is the provision of means for attaching the blades to the rotors of a turbine, in such manner that they will be properly held in the desired 30 position and at the desired angle and so arranged as to reduce leakage to a minimum degree and also insulate the same against heat.

A still further object of the invention is 35 the provision of a turbine construction such as above referred to which will be comparatively simple and inexpensive to manufacture, reliable and efficient in use and readily operated.

With the above and other objects in view, 40 the present invention resides in the novel features of construction, formations and combinations and arrangements of parts to be hereinafter more fully described, claimed and illustrated in the accompanying drawings forming a part of the present application, and in which:

Figure 1 is a face view of a portion of

one of the rotors, some of the blades being removed and others shown in section; 50

Figure 2 is a sectional view taken on the line A—A of Figure 1 and through the parts D—D of Figure 5;

Figure 3 is a transverse sectional view taken on the line B—B of Figure 1; 55

Figure 4 is a transverse sectional view taken on the line C—C of Figure 5;

Figure 5 is an edge view of one of the steel supporting members;

Figure 6 is a sectional view thereof; 60

Figure 7 is a transverse sectional view taken through the blades, looking in the direction of one of the rotors;

Figure 8 is a sectional view of an alternative construction used in small sized turbines; 65

Figure 9 is perspective view of a portion of a blade; and,

Figure 10 is a perspective view of a portion of the spacing ring. 70

Referring now to the accompanying drawings by corresponding characters of reference throughout the several views, the numeral 10 designates in general a portion of a turbine which includes the spaced rotors 75 11 and 12 which may be attached in the usual manner to a shaft (not shown).

The adjacent faces of the rotors 11 and 12 are provided with projecting rings 14 between which are formed the grooves of 80 channels 13 provided at intervals with shoulders 14'.

The rotors are preferably formed from steel or other suitable material, while the grooves 13 thereof are adapted to receive 85 the supporting members 15. These members 15 include a pair of side flanges 16 and 17, the former of which are provided with shoulders 18 interiorly tapered as shown in Figure 6. These shoulders are adapted to 90 cooperate with the oppositely tapered shoulders 14' above referred to for locking these members 15 in position. The flanges 16 and 17 are connected by circular plates 19 from which extend flexible flanges 20 provided 95 with enlarged inner sides 21 having grooves

22 formed therein for receiving the spacing rings 29 which are provided with spaced lugs 29' curved to conform to the curvature of the rotor blades 24 and between which the blades are inserted. The sides 25 of the grooves 22 are bent inwardly by means of a suitable machine for clamping the dovetailed ends 23 of the rotor blades and the correspondingly spaced lugs 29' and holding them in the desired position. Suitable packing beads are shown at 26 and are formed on the plates 19 and are adapted to fit within the grooves 27 of the supplemental supporting members 28 for the purpose of efficiently sealing the turbine against leakage.

It will be noted that the supporting members 15 and 28 are arranged alternately for cooperation with each other, as clearly shown in Figure 2 of the drawings. In applying the blades, the supporting members 15 are inserted in the grooves 13 between the shoulders 14' and are given a slight rotation so that the shoulders 18 will fit behind the shoulders 14', thus locking the assembled parts against displacement.

By referring to Figure 6 it will be seen that the shoulders 18 are shown in full line positions indicating one bevel and in dotted line positions indicating an opposite bevel for supporting blades of reverse angles.

It will be further seen that the blade supports also serve as insulating means against the heat caused by the operation of the turbine.

By referring to Figure 8 which shows an alternative construction used for small sizes of turbines, it should be noted that the reference numerals indicate the same parts as in Figure 2, but numeral 30 has been substituted for numeral 14. In this construction rings 30 are formed on the interior faces of the rotor.

In the mounting, the supporting members 15' are inserted between the rings 30 and said rings 30 are closed over said supporting members 15' forming a dovetail, thus holding the supporting members 15' rigidly in place.

From the foregoing description taken in connection with the accompanying drawings, it will be manifest that a rotor blade support for turbines is provided which will fulfil all of the necessary requirements of such a device, and it should be understood in this connection that various minor changes in the specific details of construction can be resorted to within the scope of the appended claims, without departing from the spirit or sacrificing any of the advantages of the invention.

Having thus fully described the invention, what I claim as new and desire to secure by Letters Patent is:

65 1. The herein described turbine com-

prising a rotor, said rotor having circular grooves formed therein, shoulders provided at the edges of the grooves, supporting members fitted in the grooves, shoulders provided upon the supporting members for cooperating with the shoulders at the edges of the grooves, and blades carried by said supporting members.

2. The herein described turbine comprising a rotor, said rotor having circular grooves formed therein, shoulders provided at the edges of the grooves, supporting members fitted in the grooves, shoulders provided upon the supporting members for cooperating with the shoulders at the edges of the grooves, the supporting members having grooves formed therein, and rotor blades having dovetailed ends interlocked in the grooves of the supporting members.

3. The herein described turbine comprising a rotor, said rotor having circular grooves formed therein, shoulders provided at the edges of the grooves, supporting members fitted in the grooves, shoulders provided upon the supporting members for cooperating with the shoulders at the edges of the grooves, the supporting members having grooves formed therein, rotor blades having dovetailed ends interlocked in the grooves of the supporting members, spacing rings in the last named grooves and lugs thereon disposed between the blades, substantially as and for the purposes set forth.

4. The herein described turbine comprising a pair of spaced rotors having grooves formed in the inner faces thereof, shoulders provided at the outer edges of the grooves, supporting members fitted in the grooves, shoulders provided upon the supporting members for cooperation with the first named shoulders, blades carried by said supporting members, supplemental supporting and insulating members attached to the blades, and packing beads formed upon the first mentioned supporting members and engaging the grooves in the supplemental supporting members for sealing the turbines.

5. The herein described turbine comprising a pair of spaced rotors having circular grooves formed in the inner sides thereof, shoulders provided at the edges of the grooves, main supporting members fitted in the grooves, said main supporting members comprising flanges which fit within the grooves, shoulders formed upon the flanges for engagement with the shoulders formed at the edges of the grooves, plates connecting the flanges of the main supporting members, additional flanges formed upon said plates, said additional flanges having grooves therein, blades having alternate opposed ends fitted in said grooves, rings in the grooves in contact with the blades, lugs upon the rings for holding the blades in

spaced relation, packing beads formed upon the plates of the main supporting members, supplemental supporting members attached to the opposite ends of the blades, said 5 supplemental supporting members having grooves therein for receiving the packing beads, and an interlocking engagement between the supplemental supporting mem-

bers and remaining ends of the blades, the supporting members serving to insulate 10 against heat, substantially as and for the purposes set forth.

In witness whereof I have hereunto set my hand.

ALFRED BONOM.
